(57) **CLAIM**

The ornamental design for a pelvic MRI coil, as shown and described.

DESCRIPTION

FIG. 1 is a bottom perspective view of a pelvic MRI coil showing with an environment;

FIG. 2 is a top perspective view thereof;

FIG. 3 is another bottom perspective view thereof showing in a condition of use;

FIG. 4 is a bottom view thereof;

FIG. 5 is a top view thereof;

FIG. 6 is a side view thereof;

FIG. 7 is another side view thereof;

FIG. 8 is a front view of the bottom side thereof showing in a condition of use; and,

FIG. 9 is a back view of the bottom side thereof showing in a condition of use.

The broken lines depicting straps in FIG. 1 and outlines of the patient in FIGS. 8 and 9 are directed to environment and are for illustrative purposes only; the broken lines form no part of the claimed design.

1 Claim, 9 Drawing Sheets
